Inventor Herbert Murray Harte

By John C. Gould

Attorney.

UNITED STATES PATENT OFFICE.

HERBERT MURRAY HARTE, OF MANCHESTER, ENGLAND.

PENCIL SHARPENER.

1,402,351.

Specification of Letters Patent.

Patented Jan. 3, 1922.

Application filed September 29, 1921. Serial No. 504,242.

To all whom it may concern:

Be it known that I, HERBERT MURRAY HARTE, subject of the King of Great Britain and Ireland, and resident of Manchester, in the county of Lancaster, England, have invented certain Improvements in Pencil Sharpeners, (for which I have filed in Great Britain an application for Patent No. 11,282, dated 23rd April, 1920,) of which the following is a specification.

This invention relates to improvements in pencil sharpeners, and has for an object a pencil sharpener holding the blade in such a manner that the blade edges may be adjusted without removal of the blade to vary the position of the cutting edge in relation to the pencil.

In carrying the invention into effect I provide a concave plate and a convex plate with means for securing a flat blade between them and means for pressing the whole together, so that the blade edge may, on such pressure being applied to the curved plate, project more or less according to the pressure, into a slit in a conical tube attached to or formed in one with one of the curved plates and which conical tube serves for the reception and guidance of the pencil and during the operation of sharpening.

My invention will be fully described with reference to the accompanying drawing in which,

Fig. 1. is a plan of my improved device, Figs. 2 and 3 elevations from opposite ends,

Fig. 4. longitudinal section and

Fig. 5. plan of top plate.

In accordance with my present invention I provide one of the plates *a* with a concave surface *b* and the other plate *c* with a convex surface *d* so that when the razor blade *e* is placed between them and the plates tightened up the blade is bent more or less to the curvature of the plates so that its cutting edge for the time being gives an efficient cutting action on the pencil besides enabling the keenness of the cut to be altered as desired. The plates *a* and *c* may be made of sheet metal or they may be made of cast metal or stampings and are quite independent from each other as shown in the drawing, the two plates being secured together with the blade between them by means of a

clamping bolt, screw or the like *f* and nut *g* to enable the blade to be adjusted in the manner before described. The blade may be held in the proper position by means of two or more studs *h*, usually two, in addition to the central clamping screw or bolt and such studs may be made in one with or be secured to either of the plates so that the holes *i* in the razor blade can be passed over them. Instead of the studs one of the plates may be formed with fillets or recesses *l* near the ends to hold the blade in the correct position laterally. The adjusting screw or bolt *f* determines the extent the cutting edge of the blade shall project into the slot *j* formed in the conical tubular member *k* into which the pencil is placed and turned during sharpening. The conical tubular member *k* is formed in one with one of the plates. The fillets or recesses previously mentioned may be used by themselves or in conjunction with the studs.

What I claim as my invention and desire to secure by Letters Patent:—

1. A pencil sharpening device, comprising a safety razor blade provided with holes, a pair of plates one formed convex and one formed concave between which the cutting blade is located, engaging projections on one of the plates to pass into the holes in the blade, a central screw carried by one of the plates passing through the blade and the other plate, a nut for adjusting the curvature of the blade to vary the keenness of the cut, and a slotted conical tube carried by one of the plates to guide the pencil during the sharpening operation.

2. A pencil sharpening device, comprising a safety razor blade, a pair of plates one formed convex and one formed concave between which the cutting blade is located, fillets or recesses in one of the plates to hold the blade in correct lateral position, a central screw carried by one of the plates passing through the blade and the other plate, a nut for adjusting the curvature of the blade to vary the keenness of the cut, and a slotted conical tube forming part of or attached to one of the plates to guide the pencil during the sharpening of the pencil.

In testimony whereof I have hereunto set my hand.

HERBERT MURRAY HARTE.
